UNITED STATES PATENT OFFICE.

WILLIAM H. ATKINSON, OF WASHINGTON, DISTRICT OF COLUMBIA.

AUTOMOBILE BODY.

Application filed April 29, 1926. Serial No. 105,483.

One of the objects of my invention is to provide a new type of door for automobiles which will overcome the many objectionable features of the doors now in common use.

5 Another object of my invention is to provide a door which when used on certain types of closed cars will permit freer entrance and exit than do the doors now used.

10 A further object of my invention is to provide a mounting for automobile doors which will permit the opening of the door in a convenient manner under conditions where the present types of doors operate very inconveniently as for instance when the machines are 15 parked close together when backed or headed to the curb.

Other objects and advantages of my invention will be apparent during the course of the following description.

20 In the accompanying drawings forming a part of this specification and in which like figures are used to designate like parts throughout the same, Figure 1 is a perspective view of my invention applied to an automobile having a touring body; Figure 2 is a view showing a door built in accordance with my invention partially opened both ways; Figure 3 is a side elevation of a coach body equipped with my invention, and Figure 4 is 25 a fragmentary plan view of the door shown in Figure 3. Figure 5 is a modification of my invention showing a sliding door adapted thereto. Figures 6 and 7 show respectively a top and bottom guide for the door of Figure 5.

30 In the drawing, 10 indicates the body of an automobile having the usual entrance openings 11, to the seats, which I have designated by the numeral 12. Supported within the 35 openings 11, and hinged to one side thereof is a frame 13. This frame 13 is adapted to swing upon hinges 14 and is provided with a latch 15, upon its opposite edge which engages the jamb of the opening 11 for preventing it 40 from swinging freely upon the hinges 14. The frame 13 carries a second set of hinges 16 upon which a door 17 swings. The door 17 is also provided with a latch 18 adapted to engage the jamb of frame 13 and maintain it 45 locked therein.

50 Referring more particularly to Figs. 1 and 2 it will be seen that my invention provides a door for automobiles which is capable of being opened from substantially either edge de-

pending upon the convenience of the operator. This arrangement is particularly convenient when the automobile is standing along side of another machine as when parked head-on or backed to the curb. Under these conditions the automobiles are usually parked so close to each other that the operator has difficulty in reaching the door and it frequently happens under these conditions that the door to be entered is hinged upon the edge nearest the approaching operator. In this event he is required to pass the door before opening it and where several persons are about to enter the car the door has to be closed after each entrance in order to permit the next party to get in a convenient position to again open the door and enter. When a machine is equipped with my invention the above objectionable features are overcome by operating the latch nearest the approaching operator thus opening the door upon the hinges located at substantially the far edge of the door. This permits a direct entrance to the seats through which any number of persons can then continue to enter the car without maneuvering about the swinging door as described.

55 In Fig. 2 of the drawings, I have shown both the door 17 and the frame 13 ajar. It should be understood however, that such is not a normal operation of the door. This view, is only so shown, to better illustrate the relative positions of the parts. In fact it is conceived that the latches 15 and 18 may be provided with an interlocking mechanism 60 which will prevent the opening of both the door 17 and the frame 13 at the same time.

65 Referring now to Figs. 3 and 4, the modification here shown is applied to a coach body and the frame 13 is shown as inverted. The frame 13 in Figs. 1 and 2 is shown of U shape 70 so that no overhead obstruction will be present and in Figs. 3 and 4 this U shaped frame is inverted. It should be understood, however, that the frame 13 when applied to a coach need not be of U shape. It can be a complete 75 rectangular frame if desired. This latter construction would provide a more rigid structure.

80 The frame 13 in the drawing Fig. 3 is shown with its rear vertical member 19 slightly 85 larger than its front vertical member 20. This difference in the vertical members of the frame 13 can be varied to meet any de-

sired conditions. The hinges of the door 17 can be located on a line with the back of the front seats 12 if desired, for the door 17 will only be used to gain entrance to the front compartment. It will be evident that the modification shown in this figure of the drawing, while possessing the features of the modification shown in Figs. 1 and 2 also provides the following additional advantages:

- 10 It is the practice at the present time to provide a single door on each side of the bodies of automobiles, commonly known as coaches. These doors of necessity are made larger than ordinary doors so as to permit easy access and 15 exit from both the front and rear compartments of the coach. Such a door when fully open extends out from the car a considerable distance and as a result causes great inconvenience and when opened upon a driveway 20 is in danger of being struck by a passing automobile. It is also likely to strike trees and poles when opened unless particular care is taken in parking the car at a point where no obstruction is present. As suggested above when a door of the present type is used it must be fully opened to permit easy access to or exit from at least one of the compartments of the coach. When a door built 25 in accordance with my invention is applied to a coach body and located with respect to the seats as shown in Figs. 3 and 4 it will be seen that it completely overcomes the above objectionable features, since the door can be opened from either side and thus provide access to either of the compartments without opening the door to its fullest extent. When it is desired to enter the rear compartment the rear latch is operated and with the door 30 only partly open as suggested above an easy access is provided and if it is desired to enter the front compartment the forward latch is operated, thus providing an equally convenient entrance.

When an automobile having a coach body 45 is parked end on against the curb the objectionable features referred to above are considerably aggravated by reason of the larger doors which are used on coaches. Under these conditions it is frequently a difficult 50 matter to get into the coach without having to climb over the front seat. For example, assume that the coach door is hinged upon its forward edge and that the door, due to interference, can only be opened about 30 degrees 55 or approximately to the position of the door shown in Fig. 4. With the door in this position and entrance to be had to the front compartment, it will be seen that the operator will have to climb over the front seat in order 60 to get into a sealed position, whereas, with a door of the type proposed by my invention the door can be opened upon its rear hinges and thus an easy entrance is effected.

Referring now to Figs. 5, 6 and 7, in which 65 I have shown a modification of my invention,

the door 17 is arranged to slide upon a suitable support 20 which is capable of permitting the door to move at least half its width in either direction. This modification will eliminate the objection of the swinging feature of the door as recited above and by reason of its movement in both directions it permits the use of a single sliding door and will permit easy access to either the front or rear compartments of the coach.

The support 20, in its preferred form, will support the door at its lower end and a suitable guide 21 will be provided at the top, this guide being so arranged that the door when closed will not project out beyond the limits of the coach body so as to distract from its natural lines. In order to accomplish this the support 20 and the guide 21 are provided with curved runways 22 and 23 respectively shown in Figs. 6 and 7 of the drawings, and the door 17 is provided with two projecting members or rollers 24 near its lower corners which engage the runway 22. The top of the door carries a third projecting member or roller 25 which engages the runway 23 of the guide member 21. This will permit the outer surface of the door to be moved into line with the outer surface of the body when closed.

In order to open a door mounted in accordance with this modification of my invention, the operator will grasp either handle 15 or 18 depending upon which point of the machine he wishes to enter, and, after releasing the latch he will pull the door outwardly so as to clear the body and then slide the door as is customary. This outward movement of the door is made possible by the shape of the runways at points 26. While the operated latch will permit this outward movement the trailing or unoperated latch will hold the other edge of the door in and as the door is moved lengthwise the machine, the trailing latch will disengage, thus permitting the whole door by reason of the curved runways 100 22 and 23 to assume a position parallel with the outer surface of the machine body where it can be freely moved.

In closing this type of door the operator merely slides it back into place and pushes it until the operated latch catches. During the closing operation the unoperated latch will be moved in by reason of the curved condition of the runway adjacent the portion 26 and will automatically engage its cooperating catch without any additional attention on the part of the operator.

Having now described my invention in several modified forms, I desire to have it understood that the same can be carried out by other means as for instance by providing a double set of hinges the pintles of which can be withdrawn to permit the door to swing freely on one set of hinges. The set of hinges of which the pintles have been withdrawn being the 125

equivalent of the latch when closed or as hinges when the pintles of the other set of hinges are withdrawn.

What I claim and desire to secure by Letters Patent is:—

1. A motor vehicle body having a single doorway on either side, a door for said doorway comprising a door-member and an outer frame, a seat adjacent said doorway, means co-operating with the parts of said door, whereby said doorway may be opened from substantially either jamb to permit access to said seat or to the rear of said seat depending upon the jamb from which said doorway is opened.

2. A motor vehicle body having a substantially closed compartment, a door for said compartment comprising an inner and outer member adapted to open from substantially either jamb, and front and rear seats arranged within said compartment so that access to said front or rear seats is determined by the jamb from which said door is opened.

3. A motor vehicle body having a single doorway on either side, a door for said doorway comprising an inner and an outer member, means cooperating with the members of said door, whereby said doorway may be opened from substantially either jamb, and a seat arranged within said body adjacent said doorway so that access to said seat is obtained when the doorway is opened from one jamb and access to the rear of said seat is obtained when the doorway is opened at its other jamb.

4. A door for automobile bodies comprising a single door element supported on the side of the body, a seat within said body adjacent said door, and means associated with said

door element adapted to permit it to be opened from substantially either jamb, said means being arranged to provide a minimum of interference with access to the front or to the rear of said seat as determined by the jamb from which said door is opened.

5. In an automobile body the combination of, a doorway in said body, a door for said doorway, latching and hinging means on substantially each jamb of said doorway, a seat within said body between the jambs of said doorway, and means for supporting and co-operating with said door whereby it can be opened from substantially either jamb of said doorway, to permit access to said seat or to the rear of said seat.

6. In an automobile body the combination of, a doorway in said body, a support hinged to one jamb of the doorway and latched at the other jamb, a door hinged to the latched part of said support and latched to the hinged part of the support, and a seat arranged within said body adjacent the doorway so that entry to said body on either side of said seat is determined by the manner in which the doorway is opened.

7. A motor vehicle body having a substantially closed front and rear passenger compartment, a doorway in said body, a door extending adjacent both of said compartments, and means whereby said door may be opened from either jamb to permit access to said front or rear compartment depending upon the jamb from which said doorway is opened.

In testimony whereof I have hereunto subscribed my name this 26th day of April 1926.

WM. H. ATKINSON.
